UNITED STATES PATENT OFFICE.

WALTER W. HUNZICKER, OF MANSFIELD, OHIO, ASSIGNOR TO THE OHIO BRASS COMPANY, OF MANSFIELD, OHIO, A CORPORATION OF NEW JERSEY.

TROLLEY-WIRE SUPPORT.

1,355,605.

Specification of Letters Patent. Patented Oct. 12, 1920.

Application filed November 6, 1918. Serial No. 261,326.

To all whom it may concern:

Be it known that I, WALTER W. HUNZICKER, a citizen of the United States, residing at Mansfield, in the county of Richland 5 and State of Ohio, have invented certain new and useful Improvements in Trolley-Wire Supports, of which the following is a specification.

This invention relates to a device for supporting a trolley wire for use in electric traction systems and relates more particularly to that class of devices known as trolley wire supports.

One of the objects of my invention is to provide a device which can first be attached permanently to its support and then clamped upon the trolley wire by a single operation of one of the members composing my invention.

With this and other objects set forth and herein disclosed, my invention consists in the construction and combination of parts as hereinafter described and claimed.

In installing trolley wires it is the usual custom to first set the poles and install the span wire from pole to pole or other supporting means and then to install upon the span wire or other supporting means the device used for suspending or supporting the trolley wire therefrom. The next operation is to string the trolley wire and then secure the supporting device to the trolley wire, thus anchoring and holding the same in position. It is desirable therefore, to have a device for securing the trolley wire to the span wire or other supporting means which can be operated in the simplest and hence the most economical and time-saving manner, and in my invention I bring this about by the mere operation of a single member by means of an ordinary wrench.

To show my invention more clearly I have set forth in the drawing one form of my invention as follows:

Figure 1 is a side elevation of my invention showing a trolley wire secured thereto.

Fig. 2 is an end elevation of my invention shown in Fig. 1.

Fig. 3 is a part section of my invention showing the various elements and relation theretwixen taken on the line 3-3 of Fig. 2.

Fig. 4 is a sectional view of my invention taken on line 4-4 of Fig. 1.

My invention as shown in the drawings

consists of a hanger member 1 adapted to be supported from above by means of the threaded boss 2 (Fig. 3) or the arms 2^a (Fig. 4). The form of attachment (2 Fig. 3) is one generally used in mine construction work where the hanger is suspended directly from the roof by means of an expansion or lag bolt having the lower protruding end threaded. This hanger, can, however, be modified by having arms thereon (2^a Fig. 4) extending sidewise for gripping a span wire which is ordinary and common practice or any other well known or suitable means may be provided for attachment to the well known pipe bracket 60 arm.

The hanger member 1 is filled with an insulating compound 3 and embedded in this is a stud bolt 4 provided with an enlarged head 5 and mounted in the insulation with sufficient clearance to permit of its rotation and a slight degree of vertical movement. To facilitate this action and assist in the manufacture of the device, the stud 4 and the enlarged head 5 are inclosed 65 in a metallic casing 6.

Secured to the stud 4 just below the lower face of the insulation 3 is a collar 7 provided with a plurality of vertical faces adapted to receive a wrench or other simple 75 means to rotate the collar 7 and stem 4. Below the plurality of vertical faces is a conical or beveled surface 8 adapted to contact with the lips 18 of the clamp members 13 to move the lips 18 outward.

The collar 7 is shown as secured to the stud 4 by means of a pin 9 seated in a recess 10 of the stud 4 and the recess 10 is of such size and location with respect to the pin 9 as to permit of a slight movement of 85 the collar with respect to the stud 4 so that as the jaws of the clamp are caused to grip the trolley wire the collar 7 will move relatively to the stud 4 in a longitudinal direction and press firmly against the lower face 90 of the insulation 3 with a degree of pressure depending upon the gripping action of the jaws 13 upon the trolley wire. Other means of securing the collar 7 to the stud 4 may readily be used without departing 95 from the spirit of my invention, the construction shown constituting merely the preferred form.

The lower end 11 of the stud 4 which projects below the collar 7 is screw threaded to 110

receive a suspension member 12 provided with a threaded socket, the threads of which engage the threads of the stud 4. Surrounding the suspension member 12 are two hinged or pivoted jaws 13 secured together and to the boss 12 by means of the pin 14 which passes through counterpart lugs 15 on the jaws 13. The ends of the pin 14 are shown as upset or headed at 16 in order to 10 secure all parts together.

The lower edge of the jaws 13 are provided with lips 17 so shaped as to enter and engage the grooves of a trolley wire or to encircle the same.

15 Secured to the jaws 13 is a flaring collar 18 adapted to receive the lower conical end 8 of the collar 7. The flaring collar 18 is provided with an interior surface 19 which engages with the conical surface 8 on the 20 collar 7.

The operation of my invention when installing the same in position consists in first securing the invention to such overhead support as provided which may be an expansion bolt, a depending stud, a cross span wire or a projecting bracket arm or other common and well known means used for supporting a trolley wire. The collar 7 and stud 4 are rotated in one direction sufficiently to disengage the conical surface 8 from the surface 19 of the flaring collar 18 a sufficient distance (Fig. 3) to permit the jaws 13 to open sufficiently to receive the trolley wire between the lips 17. The trolley wire 35 is then placed in position between the lips 17 and the collar 7 is rotated in the opposite direction from that previously operated, and this rotation of the collar 7 will cause the stud 4 to rotate which in turn will 40 cause the threaded suspension member 12 to be drawn upward together with the jaws 13 and the pin 14; this is brought about through the threaded connection between the stud 4 and the boss 12.

45 As the jaws 13 move upward they will finally engage the conical surface 8 of the collar 7, and the surface 8 pressing against the surface 19 of the jaws 13 will cause the jaws 13 to be expanded or forced outward at 50 the top about the pin 14 as a fulcrum and this action will cause the lips 17 to engage the groove in the trolley wire 21 and cause the collar 7 to strongly engage the lower face 20 of the insulation 3 (Fig. 4). As the rotation of the stud 7 is continued by means of a wrench applied to the collar 7, the jaws will be forced farther apart at the top and the tendency will be for the lips 17 to be forced inward toward each other, thereby increasing the gripping action upon the trolley wire 21 until the wire is securely gripped in place.

In order to disengage the trolley wire from my support, it is merely necessary to 65 reverse the operation, that is, rotate the col-

lar 7 and attach stud 4 in the reverse direction which will force the suspension member 12 downward together with the jaws 13 secured thereto, thus relieving the pressure upon the lips 18 and permitting the lips 17 70 of the jaws 13 to open outward.

I have illustrated and described only one method of carrying out my invention, still many modifications of the arrangement which the foregoing description and drawings will fully reveal and which others can, by applying current knowledge, readily adapt and which from the standpoint of the prior art, fairly constitute essential characteristics of the generic and specific aspect 80 of this invention, and therefore such adaptations should and are intended to be comprehended within the meaning and range of equivalency of the following claims.

Having thus described my invention, what 85 I claim as new and desire to secure by Letters Patent is:

1. A trolley wire support comprising in combination a hanger body, a rotatable stud secured in the hanger body but insulated therefrom, a collar secured to the stud and rotatable therewith, a conical surface on the collar, a threaded end on the stud projecting beyond the collar, a threaded suspension member mounted on the threaded 95 end of the stud and adapted to rotate relatively to the stud, a pair of jaws pivotally secured to the suspension member to engage a trolley wire, means on the jaws to coact with the conical surface on the collar and 100 means for rotating the collar and stud to draw the jaws into engagement with the conical surface on the collar and thereby move the jaws into engagement with the 105 trolley wire.

2. A trolley wire support comprising in combination a pair of clamping jaws secured together, a threaded suspension means mounted between the clamping jaws, a rotatable stud in threaded engagement with the 110 suspension means and secured to a support, a conically shaped member secured to the stud and engaging the support and jaws and adapted to move the jaws to grip a wire when the stud is rotated and the jaws move 115 toward the support.

3. A trolley wire support comprising in combination a hanger body, means to support the hanger body, insulation secured in the body, a metal shell provided with a 120 two-part cavity embedded in the insulation, a rotatable stud with an enlargement positioned in the two-part cavity and projecting therefrom, a collar secured to the stud and rotatable therewith, a conical surface on the collar, a threaded end on the stud projecting beyond the collar, a threaded suspension member mounted on the threaded end of the stud and adapted to rotate relatively to the stud, a pair of jaws secured to 125 the 130

the suspension member, a pin engaging the jaws and suspension member to secure the boss and jaws together, means on the jaws to coöperate with the conical surface on the 5 collar, lips on the jaws to engage a trolley wire and means on the collar whereby the collar and stud are rotated to draw the jaws into engagement with the conical surface on the collar, thereby moving the jaws into engagement with the trolley wire.

4. A trolley wire support comprising in combination a pair of clamping jaws adapted to clamp a trolley wire, a threaded suspension means, a pin pivotally securing the 15 jaws and suspension member together, a hanger body, a rotatable stud mounted in the suspension means and having threaded engagement therewith, insulation interposed between the stud and hanger body, a 20 conical member mounted on the stud to rotate therewith and to engage the jaws and

hanger when rotated to force the jaws into stronger engagement with the conical member to cause the jaws to clamp the trolley wire.

5. A trolley wire support comprising in combination a pair of clamping jaws to clamp a trolley wire, a threaded suspension means secured to the jaws, a pin pivotally securing the jaws and suspension means together, a supporting member provided with a rotatable stud, a member having a conically shaped portion secured to the stud and movable longitudinally thereof and rotatable therewith and engaging the supporting member and the jaws and adapted to expand the jaws into engagement with the trolley wire when the conical member and the stud are rotated.

In testimony whereof I affix my signature.

WALTER W. HUNZICKER.
